UNITED STATES PATENT OFFICE.

WILLIAM B. CHAPMAN, OF JACKSON HEIGHTS, NEW YORK.

BOILER AND METHOD OF OPERATING THE SAME.

Application filed July 29, 1926. Serial No. 125,622.

The invention in one of its aspects relates to a boiler designed particularly to be heated by the use of fine sizes of coal without, however, requiring that the coal be first subjected to pulverizing operations to reduce it to an exceedingly fine and uniform size.

The invention aims to provide a boiler wherein gaseous currents carrying suspended finely divided coal will be afforded a relatively long path of travel within the range of the heat exchange surfaces, and during which path of travel such currents will be brought into efficient contact with the boiler tubes, the coal particles which do not burn in suspension being collected in a fire bed which is conditioned and regulated as hereinafter specified.

Another object of the invention is to provide a boiler wherein the heating gaseous currents will be substantially symmetrical with regard to the tubes to be heated, in their flow through the boiler, thereby promoting uniformity of the heating action and avoiding local dead pockets, stream lines and the usual irregularity of heat distribution found in boilers of the conventional type.

According to the above features of the present invention fine sizes of coal are fed through the combustion chamber of a boiler in such manner that a large portion of the fuel particles is burned in suspension, the remaining particles dropping onto a fire bed which is maintained so deep that a certain amount of producer gas is generated, the producer gas thus formed being led past the boiler heat interchange surfaces and being mixed with the amount of air necessary to complete its combustion, the gases of combustion then reversing their direction to pass again along the heat interchange surfaces and the last pass being preferable in a downward direction whereby only the gases which have given up the greatest amount of their heat and hence have become chilled will be exhausted from the boiler.

In accordance with another feature of the invention, the fire bed is mechanically agitated in order to spread the fuel out uniformly thereover and maintain uniform conditions of combustion by eliminating blow holes, breaking up clinkers, and the ash is removed from the fire bed uniformly and at a rate conforming substantially to its rate of production thereby enabling gas to be produced which will be substantially uniform as to quality and quantity. The uniformity of

the gas production makes it possible to supply secondary air in such quantities as will be proper to complete its combustion, avoiding the inefficiency which arises out of the excess of air usually employed for combustion purposes.

The above features of the invention may be conjointly used if desired, small fuel particles being consumed in suspension and producer gas being generated from the larger sizes as above described, and mixed with secondary air to assist in burning the suspended particles.

Further objects and advantages of the invention will be in part obvious and in part specifically pointed out in the description hereinafter contained which taken in conjunction with the accompanying drawings discloses certain boiler constructions adapted to be operated in accordance with the invention; such disclosure however is to be considered as merely illustrative of its principles. In the drawings—

Fig. 1 is a central vertical section of a boiler adapted to operate in accordance with the invention.

Fig. 2 is a transverse section taken on line 2—2 of Fig. 1.

Fig. 3 is a detailed section taken on line 3—3 of Fig. 2.

Fig. 4 is a view similar to Fig. 1 but showing a modified boiler construction.

Fig. 5 is a horizontal section taken on line 5—5 of Fig. 4.

In the embodiment of the invention illustrated in Figs. 1 to 3 I have shown a boiler having an upright substantially cylindrical combustion chamber 1 surrounded by concentric annular sets of water tubes 2 and 3 which are joined at their bottoms to an annular header 4 supported by suitable masonry work, said tubes having bent portions which are joined to an upper header or drum 5 which overlies the combustion chamber 1.

The lower header 4 surrounds the fire bed shown in Fig. 1 as supported by a grate denoted generally by numeral 6, the fuel being fed in by suitable mechanism (not illustrated) through a central opening 7 in the top wall of the boiler, from whence the fuel falls axially down toward the fire bed supported by grate 6.

As above stated, the fire bed is maintained at a sufficient depth to generate carbon monoxide or producer gas, for example, from

one foot up to several feet in depth, instead of several inches as is customary, and a fire bed agitating member 8 shown as extending substantially diametrically across the fire bed 5 immediately above grate 6, is slowly turned around relative to the fire bed to condition the latter. This agitating member has a substantial upstroking action which usually extends to the top of the fire bed, and thus produces a wave-like undulating motion of the 10 fuel and ash, and the beam is also outstroking, its combined action being to distribute out fairly evenly over the fire bed the fuel which is fed in through opening 7 and to condition 15 the fire bed for uniform results. The beam also serves to grind up clinkers in the bottom of the fire bed to sizes sufficiently small to pass through the openings in grate 6 and sweeps the grate clean, being located just 20 above it.

The grate 6 furthermore is so constructed as to enable the effective size of its openings as regards ash removal to be adjusted whereby the beam 8 may be operated at the proper 25 speed to maintain uniform conditions of combustion within the fire bed, and the grate 6 adjusted to permit ash to drop through substantially at the rate of ash production, thus maintaining a fire bed of uniform depth and 30 other characteristics which will produce the uniform grade of gas essential to efficient operation.

As shown the grate 6 consists of an upper fixed section 9 having arcuate grate openings 10 therein and a plurality of sector shaped lower sections 11 slidably supported on ledges 12 (Fig. 3) and having arcuate grate openings 13, thus permitting the lower grate sections 11 to be moved back and forth 40 radially to place the grate openings 13 more or less in alignment with openings 10. The grate sections 9 and 11, however, are sufficiently spaced to permit a substantially unimpeded flow of the blast through the fire bed, the blast being shown in Fig. 1 as passing 45 into a chamber 14 beneath the grate through a pipe 15.

The agitating member 8 in the form of the invention illustrated in Fig. 1 is supported upon a hollow post 16 passing down through a central opening in the grate and supported upon a rotary table 17 which is driven by suitable gearing which need not be described in detail. The table 17 also 55 receives the ash dropping down through the grate and carries it around until pushed off by a stationary sweep 18, which pushes the ash off into an ash pit 19 which is shown as water-sealed.

60 In case coarse sizes of fuel are employed, the coal may be merely dropped in through the opening 7, or in case finer sizes are employed the coal may be fed in through an air spout directed centrally through the 65 opening 7, the lower header 4 being pro-

vided with inclined ridges 4^c which assist in grinding up the ash and preventing the firebed as a whole from turning around bodily with the agitator. In either case a central stream of fuel will pass downwardly 70 through the combustion chamber 1, as illustrated in Fig. 1, the heavier fuel particles falling onto the fire bed, and the producer gas which is formed in the fire bed will rise in an annular stream passing upwardly 75 along the heat interchange surfaces of water tubes 2. Some of the finer fuel particles passing in through opening 7 will be consumed before reaching the fire bed, thus preventing the central stream of cold fuel from 80 cooling the boiler.

The producer gas formed as above described is mixed with secondary air and its combustion thereby completed, the secondary air being shown in Fig. 1 as supplied through 85 a series of pipes 20 passing in through the walls of the boiler to points in combustion chamber 1, somewhat above the top level of the fire bed. The jets of air thus supplied form a stratum of air across the producer just 90 above the firebed, through which the producer gas must pass soon after leaving the firebed. These pipes preferably are directed tangentially, as shown in Fig. 2, in order to impart a whirling motion to the rising annular column of burning gases, thereby serving to direct the gases outwardly against tubes 2 and avoid unbalanced conditions in 95 different zones of combustion chamber 1.

After passing spirally upwardly to the top 100 of combustion chamber 1 the gases of combustion turn and pass in a slightly spiral downward direction through an annular passageway 21 between tubes 2 and 3. As shown special bricks 22 are interposed between adjacent tubes 2 in order to form a partition between the passageway 21 and the combustion chamber, which partition extends nearly to the tops of the tubes. After passing downwardly through passageway 21 105 as above described, the spent gases may be collected in an annular gathering chamber 23 surrounding lower header 4 (except at the point where ash pit 19 is located) suitable ports 24 with dampers 25 being preferably interposed between the passageway and the gathering chamber in order to enable the draft to be balanced around the boiler, by adjustment of the several dampers. The spent gases may then pass out through 110 an exhaust flue 26.

In the operation of the boiler fuel will be fed in according to the rate of consumption desired, and the speed of rotation of the agitating member 8 so adjusted as to level the 115 fuel out over the fire bed and maintain uniform conditions of combustion therein. The grate also will be adjusted to permit the removal of ash substantially at its rate of production, whereby a fire bed will be main- 120 130

tained of uniform thickness and with uniform conditions of combustion therein, which will enable gas of uniform quantity and quality to be produced. This makes it 5 possible to feed in amounts of air through pipe 20 which will be correct for completing combustion of the producer gas. The hot gaseous currents then will pass twice past the heat interchange surfaces of the boiler 10 and since the last pass is in a downward direction only those gases which have given up the greater proportion of their heat will pass down to gathering chamber 23. The lower header 4 serves the double purpose of 15 affording extra heat interchange area, and providing water cooled walls for the fire bed which prevent the undue building up of slag deposits upon such walls.

The invention is illustrated in Figs. 4 and 20 5 as applied to a boiler having an upright substantially cylindrical combustion chamber 1^a surrounded by a single annular set of boiler tubes 2^a which are joined at their bottoms to an annular header 3^a suitably supported by masonry work, and said tubes having inwardly bent tops which are joined to an upper header or drum 4^a which overlies the combustion chamber 1^a. This drum 4^a may be provided with a manhole 5^a through which 30 all of the tubes are accessible for cleaning purposes.

In this form of the invention the heating gaseous currents pass twice through the combustion chamber 1^a, one of the passes consisting 35 of a central longitudinal stream and the other consisting of an annular gaseous current or stream which encloses the central stream above mentioned and furthermore is preferably caused to follow a helical or whirling path as it travels through the combustion 40 chamber.

As shown, the combustion chamber 1^a is provided with downwardly converging bottom walls 6^a which will form a restricted 45 throat at the bottom of the combustion chamber and a restricted bottom opening 7^a through which the air for combustion is projected in an upwardly moving stream issuing from pipe 8^a. In the present embodiment 50 finely divided coal is also fed in through pipe 8^a, and the central stream above mentioned travels upwardly to the top of the combustion chamber with a sufficient velocity to float and carry along most of the fuel particles even though the latter be not reduced 55 to a uniform powdered condition. Although powdered coal of course may be used, if desired, the boiler will operate satisfactorily with coal which has been crushed merely to 60 pass through a 5 or 10 mesh screen. Coal of this fineness does not require a pulverizer for its preparation and is therefore much less expensive than powdered coal.

After reaching the top of combustion 65 chamber 1^a the stream is reversed in direction

and travels downwardly in an annular stream or current next to the boiler tubes 2^a and I prefer, furthermore, to impart a whirling or helical motion to this annular current as it passes downwardly. As shown secondary air 70 is fed in at the top of the combustion chamber by means of a series of pipes or nozzles 9^a which are directed tangentially of the combustion chamber, and therefore set up a vortex in the top of the chamber which causes 75 the downwardly moving column of air and suspended fuel to whirl in a transverse plane out against the tubes 2^a, while the descending column of burned gases is finally carried out through one or more exhaust openings 80 10^a disposed around the bottom of the combustion chamber 1^a and leading to an annular chamber 11^a, from which the spent gases finally pass downwardly through a suitable 85 number of ports 12^a spaced around chamber 11^a and leading to the exhaust flue 13^a. If desired, further semi-circular boiler tubes 14^a, connected by headers 15^a (Fig. 5) may be placed in chamber 11^a for preheating, superheating or economizing purposes. 90

The central rising stream of air and fuel takes on heat, due to combustion, as it rises and heats the annular set of boiler tubes largely by radiation. The whirling descending column of gas and fuel, however, gives up its heat to the tubes both by radiation and by direct contact therewith, and with the efficiency of the heat exchange action being largely increased, both due to the fact that the gases are swept or whirled outwardly 100 directly against the tubes and the fact that their path of travel in range of the tubes is greatly increased due to the whirl. The path of travel of the hot gases through the combustion chamber is such that they rise 105 as they take on heat and fall as they give up heat, whereby only the cold gases, which accordingly have given up the major portion of their heat, will be exhausted from the combustion chamber; thus the path of the gases 110 conform to the natural tendency of hot gases to rise and cooling gases to fall.

It will further be noted that the path of the gaseous streams and the travel of the gases is symmetrical with regard to the heating surfaces of the boiler, that is to say, the central rising stream of air and suspended fuel is substantially equi-distant from all tubes, while the whirling downwardly moving column of gas and fuel is concentric with the annular set of tubes. The hot gases therefore tend to heat all of the tubes alike and there is little or no tendency toward the formation of local hot or cold spots in the boiler. 120

The symmetrical travel of the gases is 125 maintained in leading them from the combustion chamber, the openings 10^a permitting the gases to pass substantially uniformly into chamber 11^a, from all points around the bottom of the combustion chamber, while damp-

ers 16^a associated with the ports 12^a may be adjusted to produce uniform flow downward from chamber 11^a to the exhaust flue 13^a, at different points around the periphery of chamber 11^a.

As is shown more clearly in Fig. 5, the tubes 2^a preferably are all spaced from each other to some extent and I prefer to employ in connection with the tubes, a sheet metal 10 sheathing 17^a which has semi-cylindrical depressions 18^a therein respectively receiving and closely engaging the several tubes. The surfaces 19^a of the sheathing which lie between the tubes, are exposed directly to the 15 action of the hot gases and serve to conduct further heat to the tubes. These parts 19^a of the sheathing furthermore are free to buckle more or less which will be desirable in allowing the sheathing to accommodate itself to 20 temperature changes. As shown in Fig. 5 sections of the sheathing 17 may be welded together to make up a tight housing for the boiler tubes 2.

Such fuel particles as are not carried along 25 and burned with the gaseous current, may fall downwardly through the bottom opening 7^a of the combustion chamber into an auxiliary chamber 20^a provided with a grate 21^a which is shown as being rotatable by means of 30 a gear 22^a associated therewith. The fire bed in chamber 20^a operates to form producer gas substantially as previously described in connection with Figs. 1 to 3, air under pressure being supplied through a suitable pipe 35 23^a beneath the grate and a stationary agitating member 24^a extending radially over the grate to agitate the fire bed. As the latter rotates with the grate the agitating member 24^a also serves to eject ash into a water- 40 sealed ash pit 25^a. As shown in Fig. 4 the lower walls 6^a of combustion chamber 1^a are cooled by air passing into a chamber 26^a which surrounds such walls, such cooling air passing outwardly through a pipe 27^a in 45 chamber 26^a to a blower, not shown, for supplying air under grate 21^a.

The producer gas formed in chamber 20^a passes up with the central stream of air and fuel above described, thus entering quickly 50 into the combustion which takes place in combustion chamber 1^a and preventing the great velocity of the stream issuing from pipe 8^a from blowing itself out.

While the invention has been described as 55 applied to certain specific boiler structures, it will be obvious that many changes may be made therein without departing from its principles as defined in the appended claims.

I claim:

60 1. The method of operating a boiler having a combustion chamber and boiler heating surfaces surrounding the same, which comprises projecting a central stream of finely divided fuel longitudinally through the central portion of said combustion chamber,

deflecting said stream toward the heating surfaces adjacent one end of the combustion chamber, and imparting a whirling motion thereto to cause the gases of combustion to travel back through the combustion chamber 70 in the form of an annular whirling column surrounding said first mentioned stream.

2. The method of operating a boiler having a vertical combustion chamber with boiler heating surfaces surrounding the same, 75 which comprises projecting a central stream of finely divided fuel downwardly through said chamber and deflecting said stream upwardly at the bottom of the combustion chamber, and projecting air tangentially 80 into the lower portion of the combustion chamber to set up a whirling motion in the gases therein and cause said gases to travel upwardly through the combustion chamber in an annular whirling column surrounding 85 said first mentioned downward stream.

3. In combination, annular boiler heating surfaces, a combustion chamber enclosed thereby, means disposed adjacent one end of said combustion chamber for projecting a 90 stream of finely divided fuel centrally therethrough and means adjacent the opposite end of said chamber for setting up a whirl in the gases at such last mentioned end of the combustion chamber, said combustion chamber 95 having one or more exhaust openings located adjacent the first mentioned end thereof.

4. In combination, annular boiler heating surfaces running substantially vertically, a combustion chamber enclosed thereby, means 100 associated with one end of said combustion chamber for projecting longitudinally through said chamber a central stream of finely divided fuel, means for admitting air tangentially of the chamber adjacent the 105 opposite end thereof, said chamber having one or more exhaust openings located adjacent its first mentioned end.

5. The method of operating a boiler having a combustion chamber with boiler heating 110 surfaces adjacent the same which comprises projecting a stream of finely divided fuel into said chamber to burn the more readily combustible fuel particles, maintaining a fire bed beneath said combustion chamber to receive 115 other fuel particles, passing primary air through the firebed to form producer gas therefrom, feeding the gases formed in said fire bed to said chamber, and introducing secondary air into said chamber to complete the 120 combustion of said gases.

6. The method of operating a boiler having a combustion chamber with boiler heating surfaces adjacent the same, which comprises projecting a central stream of finely divided 125 fuel through said chamber, maintaining a fire bed beneath said chamber to receive fuel particles passing downwardly therefrom and forming producer gas from such particles, and passing the gases produced from said fuel 130

back through said chamber in the form of an annular column surrounding said first mentioned stream.

7. The method of operating a boiler having a combustion chamber with boiler heating surfaces adjacent the same, which comprises projecting a central stream of finely divided fuel through said chamber, maintaining a fire bed beneath said chamber to receive fuel particles passing downwardly therefrom and forming producer gas from such particles, and introducing secondary air into said chamber to complete the combustion of the producer gas formed as aforesaid, and producing an annular column of gases surrounding said first mentioned stream.

8. The method of operating a boiler having a combustion chamber with boiler heating surfaces adjacent the same, which comprises projecting finely divided fuel into said chamber, maintaining a fire bed beneath said chamber to receive fuel particles therefrom, agitating said fire bed from beneath and removing ash therefrom substantially uniformly to form a substantially uniform grade of producer gas therefrom and mixing secondary air with said producer gas in said combustion chamber in substantially proper proportions to complete the combustion of such gas adjacent the boiler heating surfaces.

9. In combination, annular boiler heating surfaces, a combustion chamber enclosed thereby, means for admitting fuel adjacent the upper part of the combustion chamber, means for supporting a bed of fuel adjacent the bottom of the combustion chamber, and an up and outstroking agitating member rotatable with regard to the fuel bed and positioned to operate in the lower part of the fuel bed.

10. In combination, annular boiler heating surfaces, a combustion chamber enclosed thereby, means for admitting fuel adjacent the upper part of the combustion chamber, means for supporting a bed of fuel adjacent the bottom of the combustion chamber, and an up and outstroking agitating member rotatable with regard to the fuel bed and positioned to operate in the lower part of the fuel bed, together with means for admitting secondary air to said chamber somewhat above the level of said fuel bed.

11. In combination, annular boiler heating surfaces, a combustion chamber enclosed thereby, a grate disposed beneath said combustion chamber, an agitating member located over said grate and rotatable relative thereto, means for feeding finely divided fuel into the upper portion of said combustion chamber, and means for admitting secondary air into the lower portion of said combustion chamber.

12. In combination, annular boiler heating surfaces, a combustion chamber enclosed thereby, a grate disposed beneath said com-

bustion chamber, an agitating member located over said grate and rotatable relative thereto, means for feeding finely divided fuel into the upper portion of said combustion chamber, and means for admitting secondary air into the lower portion of said combustion chamber, means being provided whereby the effective size of the grate openings as regards ash removal may be adjusted.

13. In combination, boiler heating surfaces, a combustion chamber enclosed thereby, said heating surfaces also forming a heated gas passageway surrounding said combustion chamber, means for admitting finely divided fuel at the top of the combustion chamber and means for maintaining a fire bed at the bottom of the combustion chamber wherein the gases of combustion pass upwardly along the annular heating surfaces and then downwardly through said passageway to their point of exhaust from the boiler.

14. In combination, annular boiler heating surfaces, a combustion chamber enclosed thereby, means for admitting fuel adjacent the upper part of the combustion chamber, means for supporting a bed of fuel adjacent the bottom of the combustion chamber and means for mechanically conditioning said bed of fuel.

15. In combination, annular boiler heating surfaces, a combustion chamber enclosed thereby, a grate disposed beneath said combustion chamber, means for mechanically conditioning the fuel bed supported by said grate, means for feeding finely divided fuel into the upper portion of said combustion chamber and means for admitting secondary air into the lower portion of said combustion chamber.

16. The method of burning finely divided fuel, which consists in projecting said fuel into a combustion chamber, allowing the coarser particles to settle to the bottom of said chamber and form a relatively deep fuel bed thereon, generating producer gas from said fuel bed and burning said gas and the remainder of said fuel in said chamber.

17. Method of burning finely divided fuel which consists in projecting said fuel into a combustion chamber, separating the finer particles from the coarser, passing the finer particles while burning substantially twice through said chamber, collecting said coarser particles, forming producer gas therefrom and burning said gas with said finer particles.

18. A boiler having heat exchange surfaces disposed contiguous to a combustion chamber, means for feeding fuel downwardly onto a fire bed located in the lower portion of said chamber, means for forming producer gas of substantially uniform quality in said firebed, and means for supplying secondary air within said chamber to the producer gas so formed to burn the latter in said chamber.

19. The method of heating boilers which

comprises feeding fuel downwardly through a chamber having heat exchange surfaces disposed contiguous thereto, maintaining substantially uniform producer gas making conditions in the fuel bed thus formed in the lower part of said chamber, admitting air to the fuel bed and thereby forming producer gas of substantially uniform quality, and mixing secondary air with said producer gas in said chamber to complete the combustion thereof.

20. The method of heating boilers which comprises feeding fuel into a chamber adjacent heat exchange surfaces, maintaining a relatively thick firebed in said chamber, agitating the lower part of the firebed to produce a vertical undulating movement therein, withdrawing ash from the bottom of the firebed at substantially the rate of ash production, admitting air to said firebed, all to form producer gas of substantially uniform quality in said chamber, and mixing secondary air with such producer gas in said chamber to burn the latter.

25. 21. A boiler having heat exchange surfaces disposed contiguous to a combustion chamber, means for feeding fuel to a fire bed located in the lower portion of said chamber, means for forming producer gas of substantially uniform quality in said firebed comprising an up stroking agitating member working in the bottom portion of the firebed and adapted to cause a vertical undulating movement therein, and means for supplying secondary air within said chamber to the producer gas so formed to burn the latter in said chamber.

22. In combination, a vertically disposed combustion chamber, boiler heating surfaces adjacent thereto, cylindrical firebed enclosing walls disposed beneath said chamber adapted to hold a deep firebed suitable for the genera-

tion of producer gas, means operating concentrically in the firebed for agitating the same, and means for forming a stratum of secondary air across said combustion chamber just above the firebed.

23. In combination, boiler heating exchange surfaces and a combustion chamber adjacent thereto, means for maintaining a gas producing firebed at the bottom of said chamber and means for interposing a stratum of secondary air in the path of the gases arising from said firebed.

24. In combination, boiler heating exchange surfaces and a combustion chamber adjacent thereto, means for maintaining a gas producing firebed at the bottom of said chamber, means for interposing a stratum of secondary air in the path of the gases rising from said firebed and means for mechanically agitating the firebed.

25. In combination, a cylindrical combustion chamber and boiler heat exchange surfaces enclosing the same, cylindrical firebed enclosing walls disposed beneath and coaxially with said chamber, means operating symmetrically with respect to the axis of said chamber for feeding fuel to the firebed, an agitating member rotating about the axis of said chamber in the firebed, means for admitting secondary air to the gases rising from the firebed, also acting symmetrically with regard to the axis of said chamber, means beneath said agitating member for discharging ashes symmetrically from the firebed and admitting air evenly thereto, and means for withdrawing the gases of combustion symmetrically from said chamber.

In testimony that I claim the foregoing, I have hereunto set my hand this 24 day of July, 1926.

WILLIAM B. CHAPMAN.
